[57] CLAIM

The ornamental design for a hair dryer with attachments, substantially as shown and described.

DESCRIPTION

FIG. 1 is a front elevational view of a hair dryer showing my new design;

FIG. 2 is a side elevational view thereof;

FIG. 3 is a front and plan view thereof;

FIG. 4 is a back elevational view thereof;

FIG. 5 is a back end plan view thereof;

FIG. 6 is a side elevational view of the hair dryer of my new design with comb attachment;

FIG. 7 is a top plan view of the comb attachment for the dryer of my new design;

FIG. 8 is an end elevational view of the comb attachment;

FIG. 9 is a side elevational view of the comb attachment;

FIG. 10 is a bottom plan view of the comb attachment;

FIG. 11 is a side elevational view of the hair dryer of my new design with brush attachment;

FIG. 12 is a top plan view of the brush attachment;

FIG. 13 is an end elevational view of the brush attachment;

FIG. 14 is a side elevational view of the brush attachment; and

FIG. 15 is a bottom plan view of the brush attachment.
